BURNER SAFETY CONTROL APPARATUS

Du Wayne John Peterson, Grosse Pointe, Mich.,
assignor to Minneapolis-Honeywell Regulator
Company, Minneapolis, Minn., a corporation of
Delaware

Application May 6, 1948, Serial No. 25,837

9 Claims. (Cl. 158—28)

1

The present invention is concerned with a fuel burner control apparatus and more particularly with a burner control apparatus of the type to be associated with a burner having a standing pilot.

In the present day fuel burner controls, especially those employing electronic flame detectors, it is customary to provide for checking the operation of the components to insure that the apparatus is operating properly. In a copending application of John M. Wilson for "Fuel Burner Control System," Serial No. 731,998, filed March 3, 1947, there is described a burner control apparatus wherein the burner control is rendered inoperative whenever the flame detection device fails to operate or the flame detection device is falsely indicating the presence of flame. This is accomplished by employing a safety switch cutout device which is energized whenever there is a demand for operation of the burner and the flame detector does not detect flame. The safety switch cutout device is also operated whenever there is no demand for operation of the burner and the flame detection device indicates the presence of flame falsely. When such an arrangement is employed in a burner having a standing pilot flame, it is necessary to make provisions for keeping the pilot flame from operating the flame detection device when there is no demand for operation of the burner and still have the control apparatus retain the circuit checking features.

It is therefore an object of the present invention to provide a burner control apparatus which when associated with a burner having a standing pilot will check the operation of the flame detection apparatus whenever there is no demand for operation of the burner.

A further object of the present invention is to utilize the control apparatus safety switch to obtain a shutdown of the control apparatus upon a flame failure or upon failure of the combustion responsive device to operate correctly when there is no combustion affecting the device.

A still further object of the present invention is to provide an electronic detecting apparatus employing a flame sensitive circuit for indicating the presence of flame and a further circuit control for rendering the flame detection apparatus inoperative whenever there is no demand for operation of the burner.

These and other objects of the present invention will be readily apparent from consideration of the specification, claims and drawings of which:

Figure 1 is a diagrammatic showing of one particular embodiment of my invention with an improved type of failsafe circuit employed with an electronic flame detector; and

Figure 2 shows a modification of the circuit shown in Figure 1 with a photoelectric cell acting as the flame sensing device.

Referring to Figure 1, the numeral 10 represents a gas burner which receives its supply of

2

fuel through a conduit 11. Controlling the flow of fuel in the conduit 11 is an electrically operated gas valve 12 which is operable when energized to permit fuel to flow to the burner 10. A pilot burner nozzle 13 having a flame 14 emitting therefrom is provided to ignite the fuel supplied to burner 10. The burner nozzle 13 receives a continuous supply of fuel from the conduit 11 through a pilot conduit 15.

For indicating the need for operation of the burner 10 a thermostat 16 is provided. This thermostat 16 may be seen to consist of a bimetal 17 which is adapted on temperature changes to move the switch blades 18 and 19 into and out of engagement with the associated switch contacts 20 and 21 respectively. Located within the housing indicated at 22 are the main components of the control apparatus. The power supply of my control apparatus consists of a transformer 25 having a primary winding 26 connected to any suitable power source, a secondary winding 27 tapped at 28 and a further secondary winding 29 having a tap at 30. Adapted to be energized by the secondary winding 27 is a control relay 31 having a relay winding 32 and switch blades 33, 34 and 35 normally biased out of engagement with the associated switch contacts 36, 37 and 38.

Energized by the secondary winding 29 is an electronic flame detection device which may be seen to consist of a pair of electron discharge devices 40 and 41 having operative circuits therefor. The discharge device 40 may be seen to consist of an anode 42, a control electrode 43, and a cathode 44, the latter of which is energized to be electron emissive by a suitable cathode heater 45. The discharge device 41 consists of an anode 46, a control electrode 47, and a cathode 48, the latter of which is heated to be electron emissive by cathode heater filament 49. Associated with the input to discharge device 40 are a pair of condensers 50 and 51 and a pair of resistors 52 and 53. Resistors 54 and 55 are associated in a biasing relation with the input to discharge device 41. Energized by the discharge device 41 is a relay 56 having a relay winding 57 which is adapted to move switch blades 58 and 59, normally biased out of association with switch contacts 60 and 61 respectively. Switch blade 58 is normally biased into contact with a contact 62. A bypass condenser 63 is connected across the relay winding 57 to function in the normal manner by filtering the pulsating direct current flowing in the energizing circuit of triode 41. A flame electrode 75 is provided to detect the presence or absence of flame. A safety cutout device 65 is associated with the energizing circuit of relay 31 and may be seen to consist of a bimetal 66 which is adapted when heated by heater 67 to move out of supporting engagement with a pair of switch blades 68 and 69. When the bimetal 66 is so moved the switch blades will separate and open an electrical circuit. A reset but-

ton 70 is provided to put the safety device back in a circuit closing position. A resistor 76 is provided for use in the energizing circuit of the heater 67 under certain conditions of operation.

Operation of Figure 1

In discussing the operation of the present control apparatus it will be assumed first that all the components are deenergized and in a position shown on the diagram of Figure 1. It will further be assumed that the pilot flame 14 is present at the pilot nozzle 13 and is intersecting the flame sensing electrode 75. Upon a demand for heat in a space being controlled the thermostat 16 will become operative so that the bimetal 17 will sequentially move switch blades 18 and 19 into engagement with their associated switch contacts 20 and 21 respectively. This sequential movement and engagement of contacts is used to prevent any chattering tendencies in the thermostat and the relay controlled thereby. When switch blade 18 engages contact 20 and switch blade 19 engages contact 21 an energizing circuit for the relay 31 will be completed so that the switch arms 33, 34 and 35 will move into engagement with their associated switch contacts 36, 37 and 38. This energizing circuit may be traced from the upper terminal of the secondary section 27 through conductor 80, relay winding 32, conductor 81, switch contact 20, switch blade 18, switch blade 19, switch contact 21, conductor 82, switch contact 62, switch blade 58, conductor 83, conductor 84, safety switch heater 67, switch blades 68 and 69, and conductor 85 back to the lower terminal of the secondary section 27. When the relay 31 becomes energized a holding circuit for the relay is established independent of the switch blade 58 and switch contact 62 of the relay 56. This holding circuit may be traced from the upper terminal of the secondary section 27 through conductor 80, relay winding 32, conductor 81, switch contact 20, switch blade 18, bimetal 17, conductor 86, switch contact 37, switch blade 34, conductor 87, conductor 84, safety switch heater 67, switch blades 68 and 69, and conductor 85 back to the lower terminal of the secondary section 27. It will be noted that both of the last traced circuit's pass through the safety switch heater 67. This safety switch heater when energized for a predetermined length of time will move the bimetal 66 toward the right so that the switch blades 68 and 69 will open circuit and open the electrical circuit to control relay 32. To prevent continued energization of the safety switch heater 67, the relay 56, whose operational circuit will be explained hereinafter, is provided to effectively bypass the energizing current for relay 32 around the safety switch heater 67. This is accomplished by the switch blade 58 moving into engagement with switch contact 60 so that with relay 56 energized the energizing circuit for the relay 32 may be traced from the upper terminal of the secondary section 27 through conductor 80, relay winding 32, conductor 81, switch contact 20, switch blade 18, bimetal 17, conductor 86, switch contact 37, switch blade 34, conductors 87 and 83, switch blade 58, switch contact 60, conductors 88 and 89, switch contact 36, switch blade 33, and conductors 90 and 85 back to the lower terminal of the secondary section 27. Under normal operating conditions the relay 56 is energized only when there is a flame detected by the input circuit to the flame detection apparatus.

In understanding the operation of the flame detection apparatus employed with the present in-

vention it is necessary to know that a flame has certain electrical characteristics which make it more conductive in one direction than it is in another so that as far as alternating electric current passing through the flame is concerned there will be a certain amount of rectification which may be utilized to bias a control tube into and out of conduction in accordance with the presence or absence of flame. The direction of greatest electron conductivity in a flame is generally in the direction of propagation of the flame. The flame electrode 75 associated with the burner nozzle 13 serves as the flame detecting element which is operable when bridged by the flame 14 to act as a rectifier of any alternating current appearing across the gap between the electrode 75 and nozzle 13. The alternating current supplied across the gap is supplied from the lower section of the secondary 29 and the conventional current flow path may be traced from the tap 30 of secondary 29 through conductors 91 and 92, condenser 50, conductor 93, switch contact 38, switch blade 35, conductor 94, electrode 75, flame 14, burner nozzle 13, ground 95, ground 96 and conductor 97 back to the lower terminal of the secondary section 29. With alternating current flowing in the last traced circuit and flame 14 acting as a rectifier it may easily be seen that the condenser 50 will become charged so that upon the presence of flame the lower terminal of the condenser 50 will become negative and the upper terminal will be positive. This charge on condenser 50 is used to bias the triode 40 and is coupled to the input circuit of the triode 40 by a filter network consisting of a resistor 52 and condenser 51, the latter of which is connected directly between the control electrode 43 and cathode 44 of triode 40. The grid resistor 53 connected in parallel with the condenser 51 functions in the normal manner. With condenser 50 charged as described above the control electrode 43 will be biased negative with respect to the cathode 44 so that the triode 40 will be effectively non-conducting. The energizing circuit for the triode 40 may be traced from the tap 30 of the secondary 29 through conductors 91 and 98, resistor 55, conductor 99, anode 42, cathode 44, and conductors 100 and 97 back to the lower terminal of the secondary 29. When there is no current flow in the last traced circuit there will be no voltage drop across the resistor 55 which is connected directly across the input circuit to triode 41 by direct connections to the control electrode 41 and to cathode 48. With no bias voltage on the triode 41 the tube will pass current and will energize relay 56. This energizing circuit for the relay 56 may be traced from the upper terminal of the secondary 29 through conductors 101 and 102, relay winding 57, conductor 103, anode 46, cathode 48, and conductors 98 and 91 back to the center tap 30 of the transformer 29. When the relay 56 becomes energized the switch blades 58 and 59 move into engagement with their associated contacts 60 and 61 to complete the above described safety switch heater bypass circuit and an energizing circuit to the electrical fuel valve 12. The energizing circuit for fuel valve 12 may be traced from the input power line 104 through switch contact 61, switch blade 59, conductor 105, and valve 12 back to the other input power line 106. With valve 12 energized fuel will be supplied through conduit 11 to burner 10 so that the burner 10 will be operative to supply heat to the space where the temperature is being controlled by the thermostat 16.

As soon as the temperature in the space being

heated has been satisfied the thermostat 16 will be operative so that the bimetal 17 will move the switch blade 18 out of engagement with its associated contact 28. With the opening of these contacts the relay 31 will become deenergized so that the switch blades 33, 34 and 35 move out of engagement with their associated switch contacts 36, 37 and 38 respectively. When the switch blade 35 moves out of engagement with its associated contact 38 the alternating current circuit to the flame detection circuit is broken so that the flame rectifier 75 will no longer function to charge condenser 50. The charge on condenser 50 will therefore leak out through the resistors 52 and 53 so that there will be effectively no biasing voltage on the input to triode 40 and the control electrode 43 will be at approximately the same potential as the cathode 44 since they are directly connected by a resistor 53. This will mean that the triode 40 will now be conducting sufficiently to put a voltage across resistor 55 which will be negative at its upper terminal and positive at its lower terminal. This voltage on resistor 55 effectively biases the triode 41 so that its current flow is decreased below a point necessary to maintain the relay 56 in an energized position. When relay 56 becomes deenergized the switch blade 59 moves out of engagement with its associated switch contact 61 to open the energizing circuit to the electric valve 12. With valve 12 deenergized the flow of fuel to the burner 10 will be cut off and will remain cut off until the valve 12 is once again energized. With relay 31 and 56 deenergized, the apparatus is back in the position shown in the diagram and is ready for another heating cycle to take place. It will be noted that the triodes 40 and 41 are continuously maintained in an operative circuit even though the thermostat 16 is not closed and relay 31 is deenergized. This will mean that the electrical apparatus for indicating a flame will be ready to operate whenever the flame rectifier is connected to the input of the indicating apparatus. Thus, the triode, when not connected to the flame rectifier 75, will be conducting and will maintain the triode 41 non-conducting, and relay 56 will be deenergized. The flame rectifier will be cut into the circuit when the relay 31 is again energized upon a subsequent demand for burner operation.

From the foregoing explanation it can be seen that the closing of thermostat 16 by a call for heat will result in the relay 31 becoming energized. When relay 31 is energized the flame detection circuit of the detecting apparatus is closed to check and see that the standing pilot flame 14 is present. If the pilot flame is present the relay 56 will become energized to close an energizing circuit to the gas valve 12.

Operation upon flame failure

Assume that there is a demand for heat in the space being controlled by the thermostat 16 so that the bimetal 17 actuates the switch blades 18 and 19 into engagement with their respective contacts 20 and 21 and so that the relay 31 will become energized as explained above. Assume further that there is no pilot flame 14 existing at the nozzle 13. It may be seen that when switch blade 35 engages switch contact 38 upon relay 31 becoming energized and closes the flame detection circuit, with the flame 14 not present, there will be no charge placed upon the condenser 50 so that the triode 40 will be biased into the conductive range and will be maintaining triode 41 effectively nonconductive so that the relay 56 will

not become energized. As noted above, when relay 56 is deenergized the energizing circuit for the relay 31 is completed through the safety switch heater 67 which is operable after a predetermined time delay to move the bimetal 66 toward the right and permit the switch contact 68 to separate from the switch contact 69. When the switch contact 68 separates from contact 69 the energizing circuit for the relay 31 is broken and will remain so until the reset button 70 is manually depressed and the contacts are once again engaging. Also deenergized by the opening of the contacts 68 and 69 are the cathode heater circuits for the triodes 40 and 41. The cathode heater circuit may be traced from the tap 28 of the secondary 27 through conductor 107, cathode heater 45, conductor 108, cathode heater 49, conductor 109, switch contacts 68 and 69, and conductor 85 back to the lower terminal of the secondary 27. With the cathode heater circuit to the triode 40 and 41 deenergized it will be impossible under any conditions to energize the relay 56 and to bring into operation the electric valve 12.

In the event that the apparatus is operating normally when there is a demand for operation of the burner 10 and when relays 31 and 56 are energized in their normal manner let it be assumed that the flame from the burner 10 and from the burner nozzle 13 are accidentally extinguished for any reason. This will result in the relay 56 becoming deenergized since the flame 14 will no longer be charging the condenser 50 so that the triode 40 now conducting will function to bias the triode 41 below the point necessary to maintain relay 56 energized. With relay 56 deenergized the circuit bypassing the safety switch heater 67 will be opened and the relay 31 will have its energizing circuit once again completed through the safety switch heater 67 since the switch blade 58 is now engaging switch contact 62. If the pilot flame is not reignited within a predetermined time the safety switch heater 67 will have warped the bimetal 66 sufficiently so that switch contact 68 and 69 will separate and deenergize relay 31 and the cathode heater circuits for the triodes 40 and 41 as explained above.

Operation on component failure

The present apparatus is further capable of detecting component failures and rendering the apparatus inoperative when such failures occur. These component failures may involve such conditions as the grounding out or shorting out of electrode 75 to burner nozzle 13, open circuiting of the electrode 75 and conductor 94, or relay 56 remaining energized even though no flame is present.

In the event that there is a ground out condition where the electrode 75 shorts with the pilot nozzle 13 it is believed that it will be quite obvious that there will be no rectification in the flame detection circuit so that the condenser 50 will not be charged and triode 40 will be conducting sufficiently to effectively bias the triode 41 below the point necessary to maintain relay 56 energized. With relay 56 deenergized the safety switch heater 67 will have the holding current for the relay 31 passing therethrough so that the safety switch contacts 68 and 69 will open to render the device inoperative after a predetermined length of time.

A similar apparatus shutdown would occur in the event that the flame detection circuit were open circuited as when the conductor 94 should

open circuit with the electrode 75. Such an open circuit would mean that no rectification would be detected by condenser 50 and triode 40 would bias triode 41 to be effectively nonconducting so that the relay 56 is deenergized. As in every other situation described thus far with relay 31 energized and relay 56 deenergized, the safety switch heater 67 will be operative after a predetermined length of time to deenergize the entire control apparatus.

Should the relay 56 remain in the energized position due to faulty operation of the input circuit of the flame detector or faulty operation of the triode control tubes 40 and 41 with relay 31 deenergized due to the opening of the switch contact 20 and switch blade 18, the apparatus will still be rendered inoperative. This may readily be seen since an energizing circuit to the safety switch heater 67 may be traced independently of the relay 31. This circuit may be traced from the upper terminal of the secondary 27 through conductor 80, resistor 76, conductor 88, switch contact 60, switch blade 58, conductors 83 and 84, safety switch heater 67, switch contacts 68 and 69, and conductor 85 back to the lower terminal of the secondary section 27. With the safety switch heater 67 energized the switch blade 66 will once again move out from under the switch contacts 68 and 69 so that they will open circuit as explained above. With the open circuiting of the switch contacts 68 and 69 the cathode heater filaments for triodes 40 and 41 will be open and when the cathodes 44 and 48 have cooled below the electron emissive point the relay 56 will become deenergized to open the energizing circuit to the electric valve 12.

In considering the above it will be noted that the subject control apparatus is one which has a component checking feature which will render the apparatus inoperative should the flame detection relay 56 stay in the energized position when the relay 31 is deenergized. By using a circuit having component check, as the above-mentioned Wilson application discloses, with a standing pilot, the apparatus would have a safety shutdown after each start for the standing pilot would maintain the flame detection relay energized. By providing an arrangement, as here, for opening the circuit of the flame rod this condition is prevented. Further, the apparatus is still able to function in the normal manner by distinguishing from open or short conditions and flame conditions at the flame rod, and because of this there will be no operation of the flame detection relay 56 or the main valve 12 under short or open conditions at the flame rod assembly. This will be true whether occurring during operation or on shutdown.

In Figure 2, I have shown a photocell substituted in the flame electrode circuit of Figure 1. Components corresponding to components in Figure 1 carry the same reference numeral in Figure 2. The functioning of the control apparatus employing a photocell is the same as Figure 1 since the photocell will detect the presence of flame at the standing pilot and due to its rectifying action will operate in the same manner as the flame electrode 75 in Figure 1 and will not indicate a flame when an open or short circuit occurs in the photocell circuit. The flame detection circuit of Figure 2, like the flame detection circuit of Figure 1, includes the switch contact 38 and switch blade 35 of relay 31 because of the use of a standing pilot and the fact that the control apparatus comprises component checking fea-

tures. The flame detection circuit in Figure 2 may be traced from the switch contact 38 through switch blade 35, conductor 94, anode 111, cathode 112, and ground conductor 95. The ground out, fail-safe on flame failure, and component checking features will be the same in a control apparatus employing a photocell as well as the control apparatus employing a flame electrode.

It may therefore be seen that I have provided 10 a burner control apparatus for association with a burner having a standing pilot which will have component checking features for maintaining the apparatus inoperative should the flame detection relay remain energized after there is no further 15 need for operation of the burner. I have further combined with the above-mentioned feature a control apparatus that will fail safe on flame failure or circuit failure in the flame detection circuit.

20 Although I have described my invention in connection with a particular type of burner control apparatus and while it is well adapted for use there, it will be obvious to those skilled in the art that my invention could be applied to 25 any type of control apparatus to be associated with a burner having a standing pilot flame. Therefore, I intend to be limited solely by the scope of the appended claims in which I claim:

1. A burner control apparatus for use with a 30 fuel burner having a continuously burning pilot flame, a continuously operating flame indicating device, said indicating device comprising a first relay and an electric circuit which is adapted when a portion thereof is bridged by a flame to effect energization of said first relay, a second relay adapted to be energized by means indicative of the need for operation of the burner, means including said first relay adapted to render the burner operative when said first relay is energized, and means controlled by said second relay for rendering said electric circuit effective only when said second relay is energized.

2. A burner control apparatus for use with a 45 fuel burner having a continuously burning pilot flame, a continuously operative flame indicating device, said device comprising a first relay and an electric circuit adapted to be completed through a photocell which when subjected to a flame will effect with said circuit energization of said first 50 relay, a second relay adapted to be energized by means indicative of the need for operation of the burner, means including said first relay adapted to render the burner operative when said first relay is energized, and means controlled by said second relay for rendering said photocell and the electric circuit effective to detect a flame only when said second relay is energized.

3. A burner control apparatus for use with a 60 fuel burner having a continuously burning pilot flame, a combustion indicating relay, a flame indicating apparatus operating continuously and operable to energize said indicating relay on the presence of a flame, a control relay adapted to be energized by means indicative of the need for operation of the burner, means including said combustion indicating relay adapted to render the burner operative when said combustion responsive relay is energized, means common to 65 said control relay for rendering said flame indicating apparatus effective to detect a flame only when said control relay is energized, safety cutout means for deenergizing said control apparatus, means for energizing said safety cutout means, and electrical circuit means including 70 75

said relays connecting said energizing means to said cutout means when either of said relays becomes energized and the other is deenergized.

4. A burner control apparatus for use with a burner having a continuously burning pilot flame, a flame indicating apparatus, said apparatus comprising a first relay and an electric circuit which is adapted when a portion thereof is connected to means exposed to a flame to energize said first relay, a second relay adapted to be energized by means indicative of the need for operation of the burner, means including said first relay adapted to render the burner operative when said first relay is energized, safety cutout means for deenergizing said control apparatus after a predetermined time delay, means for energizing said safety cutout means, switch means common to either of said relays for completing the energizing circuit of said safety cutout means when only one of said relay means becomes energized, and means controlled by said second relay for rendering said electric circuit effective to indicate a flame only when said second relay is energized to prevent said electric circuit from energizing said first relay when said second relay is deenergized.

5. A burner control apparatus for use with a burner having a continuously burning pilot flame, first relay means adapted to be energized by means indicative of the need for operation of the burner, an electron discharge device having a cathode heater, a second relay, an electrical circuit adapted to have a portion thereof affected by the presence of a flame, means connecting said second relay and said electrical circuit to said discharge device so that said discharge device is operable to energize said second relay when flame is affecting said electrical circuit, switch means controlled by said second relay adapted to render the burner operative when said second relay is energized, safety cutout means being operable to deenergize the cathode heater of said discharge device after a predetermined time delay, further switch means controlled by either of said relays for actuating said safety cutout means when only one of said relays is energized, and switch means common to said first relay for rendering said flame sensitive circuit effective only when said first relay is energized to prevent the presence of a pilot flame from maintaining said second relay energized when said first relay is deenergized.

6. A burner control apparatus for use with a fuel burner having a continuously burning pilot flame, a flame indicating apparatus having an electrical circuit adapted to render said indicating apparatus operative when exposed to a pilot flame, relay means adapted to be energized upon the need for operation of the burner, first switch means controlled by said flame indicating apparatus adapted to render the burner operative when said detection apparatus is operative, a safety cutout device for deenergizing said control apparatus after a predetermined time delay, second switch means for energizing said cutout device either when said relay means is energized and said flame indicating apparatus indicates no flame or when said flame indicating apparatus indicates flame and said relay means is deenergized, and further switch means controlled by said relay means for rendering said flame indicating apparatus effective only when said relay means is energized to prevent energization of said cutout device when said relay means is in-

operative and said flame indicating apparatus is not operating falsely.

7. A burner control apparatus for use with a fuel burner having a continuously burning pilot flame, first relay means adapted to be energized by means indicative of the need for operation of the burner, a flame indicating apparatus comprising a flame rod circuit adapted when bridged by a flame to render said indicating apparatus operative, second relay means adapted when energized to initiate operation of the burner, means including said indicating apparatus for energizing said second relay means upon a pilot flame bridging said flame rod circuit, safety cutout means operable when energized for a predetermined period of time to deenergize said control apparatus, means including either but only one of said relay means for connecting said cutout means in an energizing circuit when only one of said relay means is energized, and switch means controlled by said first relay means connected in said flame rod circuit for rendering said circuit ineffective when said first relay means is not energized.

8. A burner control apparatus for use with a fuel burner having a continuously burning pilot flame, first relay means adapted to be energized by means indicative of the need for operation of the burner, a flame indicating apparatus comprising a photocell circuit adapted when subjected to a condition of flame to render said indicating apparatus operative, second relay means adapted when energized to initiate operation of the burner, means including said indicating apparatus for energizing said second relay means upon a pilot flame light impinging on said photocell circuit, safety cutout means operable when energized for a predetermined period of time to deenergize said control apparatus, means including either but only one of said relay means for connecting said cutout means in an energizing circuit when only one of said relay means is energized, and switch means connected in said photocell circuit for rendering said circuit ineffective when said first relay means is not energized.

9. A fuel burner control apparatus for use with a fuel burner having a continuously burning pilot flame, electrical apparatus operating continuously adapted to operate in one manner when connected to means indicating the presence of a burner flame and in another manner when not so connected or the flame is absent, a first control relay connected to said electrical apparatus and energized thereby upon the presence of flame, a second control relay adapted to be energized by means indicative of the need for operation of the burner, means including said first relay adapted to render the burner operative when said first relay is energized and means controlled by said second control relay for rendering said electrical apparatus effective to detect the presence of a flame only when said second control relay is energized.
